UNITED STATES PATENT OFFICE.

NORMAN W. CUMMINS, OF PLYMOUTH, MICHIGAN.

HOOD FASTENER.

Application filed October 9, 1925. Serial No. 61,512.

This invention relates to a hood fastener and has special reference to that class of devices located outside of a hood wall for holding it in a closed and clamped position so that it cannot become accidentally displaced nor rattle during the operation of an automobile or similar vehicle.

My invention aims to provide a simple, durable and inexpensive hood fastener or catch that is easy to install and highly efficient for the purposes for which it is intended.

The hood fastener or catch is particularly characterized by a one piece rigid clamping element provided with a compressible buffer that is placed in an active wall clamping position when the clamping element is shifted by virtue of a catch element adjustably mounted thereon and adapted for hooked engagement with the hood wall to maintain the buffer under compression so that the hood wall cannot accidentally shift.

My invention will be hereinafter specifically described and then claimed, and reference will now be had to the drawing, wherein—

Figure 1 is a front elevation of the hood fastener;

Fig. 2 is a vertical sectional view of the same; and

Fig. 3 is a plan of the hood fastener.

In the drawing, the reference numeral 1 denotes a vehicle frame or sill member about which may be attached a fender apron 2 having a stop flange 3 or the stop flange may be mounted directly on the frame 1 to serve as an abutment for the lower edge of an outwardly and upwardly opening hood wall 4.

Mounted on the fender apron or frame 1 outside of the stop flange 3 or wall 4 is a bearing having a set of upstanding ears 5, said bearing being preferably made from sheet metal cut and stamped to provide the ears 5 and another set of ears 6^a by which the bearing may be attached to its support. Mounted in the ears 5 of the bearing is a pivot pin 20 and pivotally mounted on said pin is a hooked shaped clamping member

having a long arm 6, a substantially U-shaped portion or return bend 7, and a short arm 8 terminating in a bill or tang 9. This clamping member may be made from a rigid rod bent to provide the hooked shaped configuration, and said clamping member is pivotally mounted in the bearing with its

short arm adapted to confront the hood wall 4.

Suitably mounted on the bill or tang 9 of the clamping member is a compressible buffer 10 made of rubber, leather or other yieldable material, said buffer having a button or semispherical configuration so that a portion thereof may be compressed against the hood wall 4 to hold said hood wall in engagement with the stop flange 3. The natural configuration of the buffer has been indicated by dotted lines in Fig. 2 where the buffer is shown under compression.

The long arm 6 of the clamping member has its upper end upset or otherwise shaped, as at 11 for a spring abutment 12 and encircling the long arm of said clamping member is a coiled expansion spring 13 housed within a cylinder or barrel 14. Mounted on the end of the cylinder or barrel 14 are a detachable end cap 15 and a detachable catch element 16. Any suitable means may be employed for detachably mounting or fixing the cap 15 and the catch element 16 on the ends of the cylinder 14 so long as the cap 15 serves as an opposing spring abutment whereby the expansive force of the spring 13 will at all times hold the cylinder and its catch element in a retracted position relative to the clamping element, yet permit of the catch element and its cylinder being shifted when occasion requires. The catch element 16 includes a suitable handle or grip 17 in opposed relation to a hook 18 which is adapted to engage in a substantially cup shaped keeper 19, carried by the hood wall 4 in position to be engaged when the hood fastener is swung into an active position for holding the hood wall, as shown in Fig. 2.

The expansive force of the spring 13 produces downward pressure of the hook 18 on the keeper 19 so that the hood wall 4 is held down in a closed position. This maintains the cylinder 14 approximately in parallel with the hood wall 4 and the forcible hooked engagement of the element 16 and the hood wall causes the buffer 10 to be held under compression so that there is practically no chance for the hood wall 4 to move away from the stop flange 3.

To release the hood fastener it is only necessary to pull upwardly on the handle or grip 17 and then outwardly so that the hook 18 clears the keeper 19. This outward movement of the upper end of the hood fastener has impetus imparted thereto by the

buffer 10 expanding, and when the hood fastener is tilted outwardly and downwardly on its pivot there is sufficient clearance for the hood wall 4 to be raised and opened.

5 I attach considerable importance to the simplicity of construction entering into my article of manufacture, because there is no complicated and expensive linkage to accomplish the double clamping action of my fastener relative to the hood wall.

10 The stop flange 3 constitutes an abutment or means of limiting the closing movement of the hood wall and define its position, but it is to be understood that this stop flange or 15 member may have for its equivalent the walls of a cowl and radiator adapted to be engaged by the end edges of the hood wall. I do not care to limit my invention to the precise construction or location of the stop 20 member because there are various types of such members in use that will answer my purpose.

25 One embodiment of my invention has been illustrated, but it is to be understood that the structural elements are susceptible to such changes as are permissible by the appended claims.

What I claim is:—

1. In a hood fastener, a hood wall adapted to engage a stop member, a keeper on said hood wall, a rigid hook shaped member pivotally supported outside said hood wall, a catch element adjustable on said hook shaped member adapted to be placed in engagement with said keeper, and a buffer on the hook shaped member placed under compression against the hood wall by engagement of said catch element with said keeper to retain said hood wall against said stop member.

2. In an outside hood fastener wherein a hood wall is adapted to be clamped down and against a stop member, and wherein a catch element is placed in hooked engagement with the hood wall to effect such clamping action against the stop member:— supporting means for said catch element, said means comprising a one piece rigid member having an inward return bend by which said member is pivotally supported adjacent the hood wall, and a compressible buffer on the return bend of said member adapted to be placed under compression against the hood wall.

In testimony whereof I affix my signature.

NORMAN W. CUMMINS.
